DESIGN FOR A MATERNITY JACKET

Joan Hawthorne, Watertown, Mass., assignor to Stern Made Dress Co., Boston, Mass., a corporation of Massachusetts

Application May 25, 1948, Serial No. 146,574

Term of patent 3½ years

(Cl. D3—4)

To all whom it may concern:

Be it known that I, Joan Hawthorne, a citizen of the United States, residing in Watertown, in the county of Middlesex and State of Massachusetts, have invented a new, original, and ornamental Design for a Maternity Jacket, of which the following is a specification, reference being had to the accompanying drawing, forming a part thereof, in which Figure 1 is a front view of the maternity jacket showing my new design; and Figure 2 is a back view of the same.

I claim:

The ornamental design for a maternity jacket, as shown.

JOAN HAWTHORNE.
